Patented Nov. 27, 1973

229,434

GOLF PUTTER HEAD

George C. Lrower, 2308 Pacific Ave.,
Long Beach, Calif. 90806

Filed Feb. 7, 1972, Ser. No. 225,017

Term of patent 14 years

Int. Cl. D21—02

U.S. Cl. D34—5 GN

FIG. 1

FIG. 2

FIG. 4

FIG. 5

FIG. 3

FIG. 6

FIG. 1 is a perspective view of the golf putter head showing my new design;

FIG. 2 is an elevational view showing the rear face of the golf putter head;

FIG. 3 is an elevational view showing the front face of the golf putter head;

FIG. 4 is a top plan view of the golf putter head;

FIG. 5 is a bottom plan view of the golf putter head; and

FIG. 6 is an end elevational view of the golf putter head.

FIGS. 1 and 2 are shown fragmentarily for convenience of illustration.

I claim:

The ornamental design for a golf putter head, as shown and described.
